UNITED STATES PATENT OFFICE.

OLIVER R. GRASS, OF ST. LOUIS, MISSOURI.

FUEL-SUPPLY SYSTEM FOR MOTOR VEHICLES.

Application filed November 30, 1925. Serial No. 72,176.

To all whom it may concern:

Be it known that I, OLIVER R. GRASS, a citizen of the United States, residing at St. Louis, Missouri, have invented a new and useful Fuel-Supply System for Motor Vehicles, of which the following is a specification.

This invention relates to a fuel supply system for motor vehicles.

10 The object of the invention is to provide a fuel supply system for motor vehicles having means for maintaining in the fuel tank a supply of gasoline which cannot pass to the carburetor through the normally used 15 pipe but which can be admitted to the pipe leading to the carburetor by adjustment of a valve provided for that purpose.

By use of this invention the motorist is informed when the gasoline becomes nearly 20 exhausted and is enabled to use the excess of gasoline supply which, under ordinary conditions, is sufficient to operate the engine to a gasoline supply station.

25 Other objects and advantages of the invention will appear from the following description, reference being made to the accompanying drawing, in which—

Fig. 1 is a front elevation of the invention.

30 Fig. 2 is a side elevation of the invention. Fig. 3 is a sectional view of the pipe and valve structure controlling the auxiliary supply of gasoline.

35 The gasoline tank 1 is arranged to receive gasoline through an opening provided with a removable closure cap 2 of familiar construction. An overflow pan 3 catches the overflow gasoline and has a pipe 4 extending downwardly and opening to the outside.

40 A sediment chamber 5 has a pipe 6 opening through the bottom of the tank 1 and is provided with a valve 7 which may be opened for draining and cleaning purposes.

45 The normally used pipe for conducting gasoline from the chamber 5 to the carburetor of the engine comprises a pipe section 8 from which a pipe section 9 rises to a plane above the bottom of the tank 1, and a laterally and downwardly extended pipe section 10 opening into the pipe 11 leading to the carburetor. An air vent pipe 12 from the pipe branch 9 extends upwardly and is provided with a laterally and downwardly extended portion 13 opening into the upper 50 end of the pipe 4. The part 13 of the pipe 12 is above the level of the liquid contained 55

in the tank 1, so that there will be no waste of gasoline through said pipe 12. The pipe 12 serves to prevent the gasoline from siphoning out of the tank 1 to the carburetor. 60

The pipe branch 8 is connected with the pipe branch 10 by a pipe connection 14 in which a valve 15 is mounted (Fig. 3) whereby communication to the pipe branch 10 through the connection 14 may be opened or closed, as desired. The valve 15 is provided with a handle 16 whereby the valve may be operated. 65

In normal use the valve 15 is kept closed, so that the gasoline passing from the tank 1 to the carburetor must pass around the valve 15 through the pipe branches 9 and 10. This prevents withdrawal of a certain quantity of gasoline from the tank 1. When the level of the gasoline in the tank 1 falls below the upper end of the branch pipes 9 and 10 no more gasoline can pass to the engine and the engine will stop, leaving a reserve amount of gasoline in the tank 1. The motorist may then open the valve 15 permitting use of 70 the reserve supply of gasoline which should be sufficient to enable the motorist to reach a gasoline supply station. Thus the invention serves a highly useful purpose and enables the motorist to maintain a reserve supply of gasoline at all times and without necessity of inspecting the amount of gasoline contained in the tank, as might otherwise be necessary. 75

I am aware that the invention may be varied within equivalent limits without departure from the nature and principle thereof. I do not restrict myself unessentially, but what I claim and desire to secure by Letters Patent is:— 80

1. The combination with a liquid tank having an inlet opening through the top, a pan arranged to receive overflow from said opening and having its bottom below the top of said opening, a pipe opening downwardly from the bottom of said pan, and a chamber below and opening into the bottom of the tank, of a pipe opening laterally from said chamber below the bottom of the tank, a valve for opening and closing said pipe, an inverted U-shaped pipe having its arms opening into said second pipe at the opposite sides of said valve, and having its upper portion substantially above the bottom of the tank, and a pipe extending upwardly from said U-shaped pipe and thence downwardly and opening into said first- 100

105

110

named pipe and being entirely below the upper portion of said inlet opening.

2. The combination with a liquid tank having an inlet opening through the top, a 5 pipe arranged to receive overflow from said opening and having its upper end below the top of said opening, and a chamber below and opening into the bottom of the tank, of a pipe opening laterally from said chamber 10 below the bottom of the tank, a valve for opening and closing said pipe, an inverted

U-shaped pipe having its arms opening into said second pipe at the opposite sides of said valve, and having its upper portion substantially above the bottom of the tank, and a 15 pipe extending upwardly from said U-shaped pipe and thence downwardly and opening into said first-named pipe and being entirely below the upper portion of said inlet opening.

OLIVER R. GRASS.
